UNITED STATES PATENT OFFICE.

HARRY WESTNER, OF TORONTO, ONTARIO, CANADA.

OIL-BURNER.

1,399,096.

Specification of Letters Patent.

Patented Dec. 6, 1921.

Application filed July 29, 1920. Serial No. 399,704.

To all whom it may concern:

Be it known that I, HARRY WESTNER, a subject of the King of Great Britain, and resident of the city of Toronto, county of York, Province of Ontario, in the Dominion of Canada, have invented certain new and useful Improvements in Oil-Burners, described in the following specification and illustrated in the accompanying drawings, which form part of the same.

The objects of this invention are to devise a burner which will very effectively vaporize cheap grades of oil and produce a very hot fire and which may be utilized for many purposes.

The principal feature of the invention consists in the novel construction and arrangement of parts whereby the oil which is fed under pressure is atomized and thoroughly mixed with vapor and is then subjected to the heat of the burner and brought to a high state of vaporization, the vaporized fuel being projected from a nozzle and mixed with pre-heated air.

In the drawings, Figure 1 is an elevational part vertical sectional view of the duplex burner, the section being taken on the line 2-2 of Fig. 2.

Fig. 2 is a top plan view of the device.

Fig. 3 is a plan view of the end of the fuel delivering nozzle.

In the construction of the device herein shown a double burner is illustrated, one of the burners being in section and it will be understood that the description of one applies to both.

A base plate 1 preferably of rectangular form is provided with an upwardly extending edge flange 2 and a pair of circular flanges 3 arranged one at each end. Between the circular flanges and central of the width of the base plate is arranged a pair of bosses 4 having central openings therethrough, which openings are threaded at the lower end. To either side of the bosses 4 are arranged circular openings 5 extending through the base plate.

A circular shaped and tapering member 6 is supported upon legs 7 above each of the circular portions bounded by the flanges 3, said legs fitting within the flanges and the bottom edge 8, which is here shown of serrated form, is placed above the top of the said flange 3. Supported upon each of the members 6 is a circular casing 9 formed with a tapering inner wall 10 which fits

over the top of the tapered member 6 and is secured thereto by a set screw 11.

The top 12 of the casing 9 extends horizontally inward and is provided with a central circular opening 13 and a hole 14 is arranged at one side of the central opening and preferably toward the center of the base. The outer wall of the casing 9 is hollow and forms a circular water chamber 15 to which water is fed through a pipe 16 which enters the bottom of the casing.

A block 17 is formed with a pair of downwardly projecting nipples 18 which fit into the upper end of the openings to the bosses 4 and L-shaped holes 19 extend upwardly from the bottom of the nipples and open to the ends of the block.

A tubular coil 20 is arranged within the casing 9, the bottom end thereof being connected to the adjacent hole 19 in the block 17 and the upper end extending through the hole 14 in the top of said casing, the coil being arranged centrally within the casing.

A tubular member 21 is fitted into each of the openings 5 in the base and these extend upwardly having right angularly arranged upper ends extending inwardly over the casings 9 and each having a convergent nozzle 22 in the under side of the horizontal portions arranged centrally over the opening 13 in the top of the casing 9 to direct a flow of air into the said casing.

A boss 23 is formed on the under side of the horizontal portion of the tubular member 21 and a central hole 24 in said boss receives the upper end of the coil 20.

A horizontally arranged tubular member 25 is cast integral with the top of the member 21 and connects with the hole 24 and leads to a central nozzle opening 26 arranged in the under side. A boss 27 extends upwardly from above the nozzle 26 and in this boss is threaded a needle valve 28 which regulates the flow of vaporized oil through the nozzle.

A coupling 29 is threaded into the circular opening 5 and into this coupling is threaded a tubular member 30. The member 30 is provided with a central cylindrical longitudinal orifice 31, which tapers inwardly at the upper end and leads to a plurality of fine holes 32 formed in the extremity.

A nozzle 33 is threaded into the lower end of the member 30 and is provided with a

110

- tapered end 34 having a small central opening through which oil is projected. The nozzle 33 is spaced from the inner wall of the orifice 31 in the member 30 and water or vapor is fed into the said orifice through a pipe 35 which enters the side thereof, the said pipe being connected with the water chamber 15 and supplying water at a high temperature or vapor from said chamber.
- 10 An oil pipe 36 is connected to the lower end of the nozzle 33 and is provided with a suitable regulating valve 37 to regulate the feed of the oil. The oil and water are intermingled at the point of the nozzle and are projected through the small holes in the end of the tubular member 30 and are thereby mixed to a suitable extent.
- 15 The mixture thus ejected from the member 30 passes into a chamber 38 in the coupling 29 and the upper end of said coupling is formed with a plurality of very fine holes 39 through which the vapor and oil mixture is forced, thus effecting a further mixture of same as it passes into the coil 20 through 20 the holes 19 in the block 17.

In the operation of this device the burner is first heated by igniting a suitable fuel such as gasoline placed in the cup formed by the flange 3 which thoroughly heats the coil and vaporizes the oil mixture therein to a sufficient extent to ignite the same at the mouth of the nozzle 26. The flame thus produced induces a flow of air through the tubular member 21 which mixes thoroughly with the 25 burning gas and produces a very hot flame which is projected downwardly into the casting 9. The flame striking the base is then spread outwardly around the bottom of the circular member 6 and the whole burner 30 is completely enveloped therein, thus heating the base plate and the water chamber and the air tubes 21.

The vaporized water and oil mixture is converted into a highly volatile gas within 40 the coil 20 and the water supply is maintained at a high temperature and the supply of air passing through the heated tubes is pre-heated to a high temperature before mixing with the gas.

45 The results obtained from this device are of a very desirable nature, as low grade oils can be used to very great advantage and the admixture of water with the oil creates

steam within the coil 20 and the oil vaporizing in the presence of the steam creates a 55 thorough mixture producing a highly combustible gas.

What I claim as my invention is:

1. An oil burner, comprising, a base, a circular casing open at the bottom and supported above the base and having an opening in the top, a tube having its open lower end secured in an opening in the base, said tube extending upwardly beside said casing and having its upper end extending over 60 said casing and provided with a convergent air nozzle in the under side arranged over the opening in the top of said casing, a gas nozzle supported centrally of said air nozzle, a tubular coil arranged in said casing 65 and having its upper end connected with said gas nozzle, and means for feeding liquid fuel to said coil.

2. An oil burner, comprising, a base, a circular casing open at the bottom and supported above the base and having an opening in the top, a water chamber surrounding said casing, an air tube arranged beside said casing and having a nozzle directed downwardly toward the opening in the top 70 of said casing, a gas nozzle arranged centrally of said air nozzle, a tubular coil arranged within said casing having one end connected with the gas nozzle, an oil feed connected with said coil, a water pipe connecting said water chamber with said coil, and a mixing chamber arranged between 75 said feeds and the coil.

3. An oil burner, comprising, a base, a casing supported above said base, an air tube 80 leading upwardly beside said casing and extending over the top thereof and having a nozzle projecting downwardly, a vaporizing coil arranged within said casing, a gas nozzle arranged in the head of said air tube 85 and adapted to direct a flow of gas downwardly centrally of the air nozzle, a water chamber surrounding said casing, a feed nozzle connected with said coil having an inner nozzle leading from the oil supply 90 and an orifice surrounding said oil nozzle connected with the water chamber, and a finely perforated member arranged at the inward end of the feed nozzle.

HARRY WESTNER.
